UNITED STATES PATENT OFFICE.

HERBERT H. WATSON, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

WEFT DETECTOR IN TRANSFERRER ARM.

Application filed December 27, 1926. Serial No. 157,092.

This invention relates to improvements in weft detectors for regularly moving loom transferrer arms and it is the principal object of the invention to provide a mounting 5 which will hold the detector in proper yarn engaging position but will permit the same to move forwardly with the yarn as the lay advances.

In weft detectors of the kind set forth in 10 patent to Ryon #1,372,316, the transferrer arm is brought down on every detecting beat of the loom to present the detector to the yarn through the top of the shuttle. The lay undergoes an appreciable movement during 15 the time that the detector is in contact with the yarn which results in an undesirable amount of wear when the yarn is fine. It is an important object of my invention to mount the detector on a resilient device 20 which will permit the yarn engaging portion to move forwardly or rearwardly with the bobbin to avoid this objectionable wear.

It is a further object of my invention to provide a supporting arm movably mounted 25 on the transferrer and having a detector support secured thereto by means of a connection which is not subject to wear and does not require oiling, thus preventing the possibility of staining the weft. A still further 30 object of the invention is to provide a detector which can be easily replaced and not affected by accumulations of lint.

It is a more particular object of the invention to provide a coil spring located between 35 the yarn engaging portion of the detector and the carrier lever therefor and having engagement with non-circular parts of the supporting lever and detector to hold the latter in proper alignment, said spring 40 also acting to cushion any rebound of the detector.

With these and other objects which will appear as the description proceeds, my invention relates to the arrangements and combinations of parts hereinafter set forth, and more particularly pointed out in the claims.

In the accompanying drawings, wherein a convenient embodiment of my invention is shown,

50 Fig. 1 is a vertical central section through that portion of the transferrer arm lying parallel to and above the shuttle when the

latter is on the magazine side of the loom and showing the detector in engagement with a sufficient supply of weft, 55

Fig. 2 is a view similar to Fig. 1 but with the detector moved to indicating position, the supply of weft being insufficient,

Fig. 3 is a vertical section on line 3—3 of Fig. 1, 60

Fig. 4 is a detail top plan view taken in the direction of arrow 4 of Fig. 1,

Fig. 5 is an enlarged horizontal section on line 5—5 of Fig. 2, and

Fig. 6 is an enlarged vertical section on 65 line 6—6 of Fig. 5.

Referring to the drawings the transferrer arm 10 is provided with vertical walls 11 between which extend a yarn engaging tip 12 and a bobbin butt engaging heel 13. An 70 indicating plunger 14 is slidably mounted in a bore 15 extending horizontally through a portion of the transferrer arm and is normally urged to move to the right from the position shown in Fig. 1 by a compression 75 spring 16. Said spring is interposed between a web 17 of the transferrer arm and a shoulder 18 of the plunger head and a pin 19 extending through the plunger is positioned to engage said web 17 as shown in 80 Fig. 2 to limit outward movement of the plunger.

A latch 20 is pivoted as at 21 to the transferrer arm and lies between the walls 11, 85 said latch having a hook 22 to be received by a notch 23 formed in the plunger and having also a depending tail 24. The latch is counterweighted so that it tends normally to move into the position shown in Fig. 1 where it will restrain movement of the 90 plunger 14 and hold the same in non-indicating position.

A carrier lever 25 is pivoted as at 26 to the transferrer arm and has a finger 27 positioned for engagement with some portion of 95 the transferrer arm when the carrier is raised. Said lever is held in raised position by a tension spring 28 one end of which is passed around a lug 29 on the carrier lever 25 and the other end of which is secured to 100 the transferrer arm as at 30.

During normal operation the transferrer arm is brought downwardly on each detecting beat of the loom by mechanism not

shown herein but fully set forth in the aforesaid patent to Ryon. As the transerrer arm reaches the bottom of its stroke the lever 25, being free to move downwardly, continues its movement toward the bobbin B to present the weft detector to the weft.

The weft detector comprises a yarn engaging unit 40 having a notched weft engaging lower surface 41 and an upwardly extending trip 42 on the right hand side thereof. Said trip is adapted for engagement with the tail 24 at the time of indication of weft exhaustion. The left hand portion of the unit 40 extends upwardly and is non-circular in cross section as indicated in Fig. 5, having the lower closed coils 43 of the supporting spring wound closely therearound.

The spring 44 may be as shown in Fig. 1 and has the central portion provided with open coils while the upper end of the spring is similar to the lower end, being wound in closed coils 45 which hug the non-circular depending portion of the supporting lever 25 as shown in Fig. 5. By means of the non-circular portion of the lever and detector unit the latter is held in proper alignment with regard to the axis of the bobbin being detected. The closed coils lie in corrugations 46 formed in the spring engaging portions of the detector unit and supporting lever, both of said portions being similar in cross section to the showing in Fig. 5.

When sufficient weft is present the detector unit will be held against movement longitudinally along the bobbin, but at exhaustion of weft said unit will slide along the bare bobbin into contact with tail 24 to trip the latch and release the plunger 14, as shown in Fig. 2. During this movement the lay advances a slight amount and may carry the detecting unit with it due to the yielding of spring 44, but the tail 24 is wide enough to be engaged by the trip 42 in any lateral position of the detector unit relatively to the transerrer arm, see Fig. 4.

From the foregoing it will be seen that I have provided a weft detector on the transerrer arm wherein the detecting unit has interposed between the same and the transerrer arm a resilient element which normally holds the detector in proper position but which permits the same to move to engage the tail 24 and lift the latch to release the plunger when the unit 40 engages a bare bobbin. The resilient element also permits the detector to move with the bobbin and thus avoid frictional contact and consequent wearing usual in this type of feeler. Furthermore, it will be seen that the connection between the detector and its carrier is of such a nature as not to require lubrication, and that the detector can be readily removed and replaced.

Having thus described my invention it

will be apparent that changes and modifications may be made therein by those skilled in the art without departing from the spirit and scope of the invention, and I do not wish to be limited to the details herein disclosed but what I claim is:

1. In weft detecting mechanism for a loom having a transerrer arm receiving a regular movement toward the surface to be detected each detecting beat of the loom, a weft engaging detecting unit, a coil spring having one end connected to the unit, and connections between the other end of the coil spring and the transerrer arm, said coil spring constituting the only support for said detecting unit and said spring and detecting unit being freely suspended from the connections to be movable as a whole in any direction. 70

2. In a weft detecting mechanism for a loom having a transerrer arm receiving a regular movement toward the surface to be detected each detecting beat of the loom, a carrier lever pivoted to the transerrer arm, a yarn engaging detecting unit, and a coil interposed between the unit and the lever and constituting the only support for said detecting unit. 85

3. In a weft detecting mechanism for a loom having a transerrer arm receiving a regular movement toward the surface to be detected each detecting beat of the loom, a carrier movably mounted on the transerrer, a detecting unit to engage the yarn, and a resilient support capable of movement in all directions interposed between the unit and the movable carrier. 95

4. In a weft detecting mechanism for a loom having a transerrer arm receiving a regular movement toward the surface to be detected each detecting beat of the loom, a carrier movable with respect to the transerrer arm, a detecting unit to engage the yarn to be detected, and a flexible supporting element between the unit and the carrier yieldable in all directions, whereby said unit may move in any direction in which the surface being detected moves. 105

5. In a weft detecting mechanism for a loom having a transerrer arm receiving a regular movement toward the surface to be detected each detecting beat of the loom, a carrier movable on the transerrer and having a non-circular portion, a detector unit having a non-circular portion, and a coil spring interposed between the unit and the carrier and having holding engagement with the non-circular portions of said carrier and unit to hold the latter in alignment with the surface to be detected. 115

6. In a weft detecting mechanism for a loom having a transerrer arm receiving a regular movement toward the surface to be detected each detecting beat of the loom, a carrier lever having a non-circular portion, 130

a weft engaging detecting unit having a non-circular portion, a coil spring formed with closed coils to engage the non-circular portions and having open coils between the 5 non-circular portions, whereby the detecting unit is held in alignment with the surface to be detected and is capable of movement with said surface.

7. In weft detecting mechanism for a loom having a transferrer arm receiving a regular movement toward the surface to be detected each detecting beat of the loom, a weft detecting unit, a carrier therefor movable with respect to the transferrer, and a

10 resilient support interposed between the carrier and the unit having the ends thereof fixed with respect to the carrier and the unit, said detector being movable relatively to the carrier due to the resilience of the 15 support.

8. In weft detecting mechanism for looms, a member movable downwardly toward the surface to be detected at periodic intervals, a detecting unit to engage the surface to be

20 detected, and flexible connections between 25

the detecting unit and member and constituting the only means of support for said unit, said connections being capable of movement in all directions, whereby the detecting unit may move with the surface to 30 be detected and in contact therewith as said surface moves under the member and said detecting unit and connections being freely suspended from the member to be movable as a whole in all directions.

9. In weft detecting mechanism for a loom having a transferrer arm receiving a regular movement toward the surface to be detected each detecting beat of the loom, a carrier movable on the transferrer arm, a detector unit, and a coil spring interposed between the carrier and unit and having closed coils to engage the carrier and unit and having open coils between said carrier and unit and constituting the only means of support 40 for said unit.

In testimony whereof I have hereunto affixed my signature.

HERBERT H. WATSON.
